Primary Examiner — T. Chase Nelson*Assistant Examiner* — Ania Aman(74) *Attorney, Agent, or Firm* — Dinsmore & Shohl LLP**CLAIM**

The ornamental design for a candle jar, as shown and described.

DESCRIPTION

FIG. 1 is a perspective view of a candle jar illustrating our new design;

FIG. 2 is a front side elevational view thereof;

FIG. 3 is a back side elevational view thereof;

FIG. 4 is a left side elevational view thereof;

FIG. 5 is a right side elevational view thereof;

FIG. 6 is a top planar view thereof;

FIG. 7 is a bottom planar view thereof;

FIG. 8 is a perspective view of a second embodiment thereof;

FIG. 9 is a front side elevational view thereof;

FIG. 10 is a back side elevational view thereof;

FIG. 11 is a left side elevational view thereof;

FIG. 12 is a right side elevational view thereof;

FIG. 13 is a top planar view thereof; and,

FIG. 14 is a bottom planar view thereof.

The broken lines depict environmental structure that forms no part of the claimed design.
